UNITED STATES PATENT OFFICE.

BENNIE CLAUD NUGENT, OF TAFT, CALIFORNIA.

SUCKER-ROD TWISTER.

Application filed May 22, 1924. Serial No. 715,243.

My invention relates to the art of pumping oil wells, and an object of the invention is to provide means by which the sucker rods of an oil well may be rotated during pumping for the purpose of evenly distributing the wear on the rods, tubing and the pump barrel and plunger.

In the pumping of oil wells, it is common practice to suspend a string of sucker rods inside the tubing of the well, these sucker rods being attached through a polish rod and suitable suspension means to the walking beam of the well, the pump rod passing downwardly through a suitable stuffing box at the upper end of the tubing. The well is generally not perfectly vertical and in some cases has more or less well defined bends or kinks therein. As a result, the sucker rods are very likely to rub at certain points on the tubing, and where the rods are suspended without rotation, the sucker rods tend to wear on one side. By slowly rotating the sucker rods during pumping, I am able to distribute this wear evenly around the rod.

Substantially every oil well produces some silt or sand and it often happens that a grain of sand works in between the plunger and the inner wall of the pump barrel. Where the rods are suspended without rotation, this grain of sand tends to move up and down in substantially the same path, soon cutting a groove in the wall of the barrel or in the outer surface of the plunger. These grooves, if sufficiently deep, are likely to cause leakage of the pump, and it is an object of my invention to avoid them. This I accomplish by a slow rotation of the rods.

Further objects and advantages will be made evident hereinafter.

Referring to the drawing which is for illustrative purposes only,

Fig. 1 is a view of my invention installed in an oil well.

Fig. 2 is a section on an enlarged scale through a portion of the device used in practicing my invention.

Fig. 3 is a side view of the same.

In the pumping of oil wells, a walking beam 11 is provided, the end 12 of this beam moving up or down for the purpose of reciprocating, through suitable mechanism, a polish rod 13, which passes through a stuffing box 14 and down into tubing 15 of the well. In the practice of my invention, I secure on the upper end of the polish rod 13 a split nut 14', which rests upon a ball bear-

ing 15'. The ball bearing 15' is supported upon a bearing 16 consisting of a casting having arms 17 and a downwardly projecting body 18. Reins 19 which may be formed of wire rope extend upwardly from the arms 17 and are suitably secured to the end 12 of the walking beam 11. A beveled gear 20 is secured by any suitable means, such as a set screw 21, to the polish rod 13 below the end of the body 18. A bevel pinion 22 is mounted to mesh with the gear 20 and to turn freely on a stud 23, secured in the body 18. Also turning freely about the center of the pinion 22 is a lever 31. Mounted to turn on a pin 32 in the lever 31 is a pawl 33. This pawl is so formed that it actuates the bevel pinion 22 when turned in a counter clockwise direction, as viewed in Fig. 3, slipping over the teeth of the pinion 22 when actuated in a clockwise direction. To prevent the lever 31 from swinging lower than a substantially horizontal position, I provide a stop 36 which may, as shown, be in the form of an arm 35 extending from the bearing 16. The handle 35 of the lever 31 is of sufficient length to strike against a stop 36. This stop may be a part of the derrick structure, or it may be especially erected for the purpose of actuating the lever 35.

The method of operation is as follows. The parts being assembled as shown, the walking beam 11 being actuated by any suitable means, not shown, the bearing 16 is moved up and down, raising and lowering the polish rod 13, and the pump rods and plunger secured thereto, but not shown. As the polish rod 13 and its associated parts move downwardly, the end of the lever 35 strikes upon the stop 36 and the lever 35 is rotated in a counter clockwise direction, thus rotating the polish rod 13 through the gears 20 and 22. The gears having been rotated, the lever 35 falls downwardly by its own weight as the associated parts move upwardly. A slow but positive rotation of the sucker rods is thus produced, this rotation having the beneficial effects previously referred to.

I claim as my invention:

1. A sucker rod rotor comprising: a polish rod; a bearing on which said polish rod is suspended and retained against longitudinal movement relative to the bearing; means for suspending said bearing from the walking beam of a derrick; a bevel gear fixed to said

polish rod; a bevel pinion supported on said bearing and meshing with said bevel gear; a lever turning about the same axis as said pinion; a pawl carried by said lever engaging said pinion; and a post so fixed as to be struck by said lever as said bearing is reciprocated and thus actuate said lever, said post being adapted to engage and swing said lever at the lower end of reciprocation of said bearing.

2. A sucker rod rotor comprising: a polish rod; a bearing through which said polish rod passes and in which said polish rod is free to turn, the bearing and polish rod being secured against relatively longitudinal movement; means secured on said polish rod and resting upon said bearing for suspending the weight of said polish rod on said

bearing; means for suspending said bearing from the walking beam of a derrick; a bevel gear fixed to said polish rod; a bevel pinion supported on said bearing and meshing with said bevel gear; a lever turning about the same axis as said pinion; a pawl carried by said lever engaging said pinion; and a post so fixed as to be struck by said lever, as said bearing is reciprocated, and thus actuate said lever, said post being adapted to engage and swing said lever at the lower end of reciprocation of said bearing.

In testimony whereof, I have hereunto set my hand at Fellows, California, this 25 day of April, 1924.

BENNIE CLAUD NUGENT.
